REVERSIBLE GEAR PUMP

John A. Lauck, Shaker Heights, and James A. Compton, South Euclid, Ohio, assignors to Borg-Warner Corporation, Chicago, Ill., a corporation of Illinois

Application November 19, 1949, Serial No. 128,442

7 Claims. (Cl. 103—3)

1

This invention relates to a reversible gear pump, and more particularly to a reversible gear pump arranged to permit reversal of operation without incurring any loss of efficiency.

It is sometimes desirable to provide a gear pump in which the direction of delivery of discharge may be readily changed, or which may be driven by a motor turning in either direction without affecting the direction of discharge. It will be readily apparent that such a pump is more adaptable than a non-reversible pump. However, heretofore most pumps in which the delivery direction may be reversed have required reversing the direction of rotation of the driving shaft and interchanging the discharge and inlet sides, the reversible feature primarily comprising designing the pump so that loss of efficiency is held to a minimum in changing direction of delivery. At best, such pumps are a compromise arrangement and, requiring substantial symmetry of design on the inlet and the outlet sides, are, consequently, less efficient than conventional, non-reversible pumps. On the other hand, where a conventional pump is to be driven by a motor turning in the opposite direction of rotation from that for which the pump is intended, this ordinarily entails reversal of delivery direction, which result may not be desirable. Thus, such a pump is not adaptable to be driven by a motor rotating in either direction without a change in the direction of discharge.

An object of the present invention is to provide a fully reversible intermeshing gear type pump, which does not involve sacrifice of efficiency in either direction of operation, and which may be driven by a mechanism turning in either direction without affecting the direction of discharge.

In accordance with one embodiment of this invention, an intermeshing gear pump may be provided wherein both pump gear shafts are provided with driving splines, both splines being positioned on the same side of the pump gears. The pump is arranged so that the mounting flange may be rotated 180° with respect to the pump body to engage either of the driving splines with a splined driving shaft extending through the flange. In this manner, the pump gears may be always driven in the same direction with respect to their associated bearings and housing, thereby, among other advantages, permitting localizing wear on the inlet side and permitting restricting the area of the high pressure zone at the discharge port, whereby journal loads and over-all wear are maintained at a low level, while

2

at the same time permitting reversal of the delivery direction or permitting use of a driving mechanism rotating in either direction.

Other objects and advantages of the present invention will be apparent from the following detailed description taken in conjunction with the drawings wherein:

Fig. 1 is an axial, sectional view partially in elevation showing an intermeshing gear pump constructed in accordance with one embodiment of this invention;

Fig. 2 is a sectional view similar to Fig. 1, showing, however, the relative position of the parts with the mounting flange rotated 180° from the position shown in Fig. 1 to engage the driving spline with the other of the pump gear shafts;

Fig. 3 is a transverse, sectional view taken substantially along the line 3—3 of Fig. 1;

Fig. 4 is a transverse, sectional view taken substantially along the line 4—4 of Fig. 2; and

Fig. 5 is a view similar to Fig. 3, showing, however, the relative position of the parts with the gear housing rotated 180° with respect to the mounting flange from the position shown in Fig. 1.

Referring now to the drawings, and particularly to Figs. 1 and 3 thereof, an intermeshing gear type pump is there illustrated comprising a housing 5 of generally conventional external and internal configuration and having mounted on the left end thereof a mounting flange 6, whereby the pump may be secured to a motor or other mechanism for rotating the pump gears. A pair of intermeshing pump gears 7 and 8 are disposed within the pump housing 5 and each has positioned on either side thereof a pair of suitable bushings 9 and 10, respectively. In the embodiment illustrated, the bushings are of the type having a tubular body and flanged gear side face engaging portions, and one set of the bushings may be made pressure loadable and axially movable in accordance with U. S. Patent No. 2,420,622 to Roth et al., where it is desired to make the pump of the pressure loadable type. The gears 7 and 8 may have their supporting shafts 12 and 13, respectively, integrally formed therewith, as shown in Fig. 1, and the shaft portions 12 and 13 are journaled in the hollow bushings 9 and 10. The pump housing has formed therein an inlet aperture 14 and a discharge aperture 15, the aperture 14 being positioned on the right side, as viewed in Fig. 3, and the discharge aperture 15 being positioned on the left side of the housing, wherein the pump is shown arranged for clockwise rotation of the lower pumping gear. Suitable sealing means are associated with the bush-

ings to prevent leakage as is well known in the art.

In accordance with the present invention, each of the shaft members 12 and 13 associated with the pumping gears 7 and 8, respectively, have fixed thereto and preferably integrally formed therewith, externally splined terminal portions or couplings 16 and 17, respectively. In a conventional pump, of course, only one of the pump gear shafts is provided with a splined coupling portion. The splined couplings 16 and 17 project to the left beyond the housing 5, the lower coupling 17 extending into the right end of an aperture 18 formed through the lower portion of the mounting flange 6, as viewed in Fig. 1, while the upper coupling member 16 is received in a cylindrical recess 20 formed in the mounting flange 6. In the arrangement of the pump parts shown in Fig. 1, the gear 8 is the driving gear and accordingly, the coupling 17 is connected to a suitable source of power through a short coupling shaft 21, the right end portion of which is provided with an internally splined cylindrical recess 22 into which the splined coupling 17 extends. Rotation of the coupling 21, by a motor or other driving mechanism (not shown) in a clockwise direction, as viewed in Fig. 3, causes the pumping gears to be rotated to pump fluid from the inlet 14 to the outlet 15 of the pump.

It has been found in practice desirable to seal the short coupling shaft 21 to the mounting flange 6, and for this purpose an annular seal assembly 23 is positioned about the right portion of the coupling shaft, the seal assembly 23 being retained by an inwardly extending, annular flange 24 integrally formed with the left side of the mounting flange 6 at the left end of aperture 18. The seal assembly is retained at its right end by a peripheral flange 25 integrally formed with the coupling shaft 21 adjacent its right end. A helically coiled spring 26 mounted in an axially extending recess 27 formed in the left end of the coupling 17 of gear 8 bears at its outer end against the inner side of the recess 22 formed in the coupling shaft 21, thus urging the flange 25 against the right end of seal assembly 23 and retaining the seal assembly tightly in position. A similar recess 28 is provided in the left end of coupling 16 to receive spring 26, when the gear 7 is to be the driving gear.

In operation, the pump housing 5 is mounted on a motor housing (not shown) or other suitable supporting structure by the mounting flange 6. Because in the operation of the pump, there may be some leakage past the bushings which might damage the motor, it has been found desirable to provide a drain and thus the left side of the mounting flange 6, as viewed in Fig. 1, is provided with a large, annular recess 30 located substantially coaxially of the coupling shaft 21 and having connected thereto at its lower side a short passage 31 leading to a drain plug 32, threaded into the lower side of the mounting flange. Connected to the recess 30 at its upper side is a somewhat longer passage 33 extending upwardly to a drain plug 34. When the pump is used in the position shown in Fig. 1, then oil or other fluid which leaks past the bushings may be drained by removing the plug 32. On the other hand, when the pump is operated in the position illustrated in Fig. 2 and Fig. 4, then the passage 33, being then at the lower side of the pump, serves as the drain passage and by removal of the plug 34, escaped oil or other fluid may be removed. It will be understood, of course, that either of the passages 75

31 or 33 may be connected to a drain line leading to the sump where suitable.

When the pump parts are assembled as shown in Figs. 1 and 3, then, as aforesaid, rotation of the shaft coupling 21 in a clockwise direction will cause the gear 8 to be rotated in a clockwise direction, and conversely, the gear 7 to be rotated in a counterclockwise direction, thus pumping fluid from inlet 14 to outlet 15. In the event it becomes necessary to drive the pump from a motor having a reverse direction of rotation from that suitable for the pump arrangement shown in Fig. 1, the housing 5 is moved to the right, as viewed in Fig. 1, by removing suitable mounting bolts (not shown) by which the housing is attached to the mounting flange 6. The flange 6 is then rotated 180° and the parts reassembled. In the reassembled position, the parts occupy the relative positions shown in Figs. 2 and 4.

From Figs. 2 and 4, it will be evident that in this reverse position of the pump, the splined coupling 16 is now engaged with the shaft coupling 21, whereas the splined coupling 17 is received in the cylindrical recess 20. From Fig. 4 it will be evident that rotation of the driving shaft, now associated with the upper pumping gear 7, in a counterclockwise direction, will cause rotation of the gear 7 in a counterclockwise direction, thereby rotating the gear 8 in a clockwise direction, in the same manner as in the arrangement of parts shown in Figs. 1 and 3. The direction of delivery and the direction of gear rotation relatively to the associated bushings thus remain unchanged.

If the shaft coupling 21 in the arrangement shown in Fig. 4 be rotated in a clockwise direction, as previously described in conjunction with Figs. 1 and 3, then it will be evident that pumping will result in a transfer of fluid from the discharge passage 15 to the inlet 14. Ordinarily, this would be of no advantage and might result in a considerable loss of efficiency where the pump's normal inlet and discharge apertures are particularly designed for maximum efficiency in which case they will be of somewhat different size and configuration. Also, where a pump has been run for any length of time in one direction, the parts tend to wear in and a reversal of direction of rotation of the gears thereafter results in a serious loss of efficiency and greatly accelerated wear. These characteristics, of course, are true of any intermeshing gear type pump. Thus, while reversal of the direction of rotation of the pumping gears is possible in the arrangement illustrated, it is not generally intended.

Conversely, if the mounting flange 6 be left in the position shown in Fig. 1 and the pump housing 5 instead is revolved 180° with respect to the mounting flange 6 from the position shown in Fig. 1, then the parts will be in the position illustrated in Fig. 5 and rotation of the coupling shaft 21 in a counterclockwise direction, that is, the opposite direction from that intended with the arrangement illustrated in Fig. 3, will cause delivery of fluid from the inlet 14 to the outlet 15, which latter outlet would then be positioned on the right side of the pump, as viewed in Figs. 3 and 4; and thus the direction of delivery would be reversed without reversing the direction of rotation of the pump gears.

From the foregoing, it will be evident that the novel pump arrangement in accordance with this invention provides an exceptionally adaptable

pump, and more particularly one in which either of the pumping gears may be the driven gear, thus permitting the direction of delivery to be reversed while permitting the gears to continue to rotate in the same direction as previously, and permitting the use of the pump with a driving mechanism turning in either a clockwise or counterclockwise direction without affecting the direction of rotation of the pump gears.

Where herein the various parts of this invention have been referred to as being located in a right or a left position, it will be understood that this is done solely for the purpose of facilitating description and that such references relate only to the relative positions of the parts as shown in the accompanying drawings.

While but one embodiment of this invention has been shown and described, it will be understood that many changes and modifications may be made therein without departing from the spirit or scope of the invention.

What is claimed is:

1. In a gear pump, a pump housing containing a pair of adjoining, substantially cylindrical chambers, said housing having a pair of ports formed therein on opposite sides thereof and communicating with said chambers, a pair of intermeshing pumping gears in said chambers, bearing bushing and end plate defining means associated with said pumping gears and supported in said housing, a shaft drivably associated with each of said pumping gears and rotatably supported in the associated bushings, a coupling termination formed on each of said shafts and extending beyond one end of said housing, said terminations being each located at the same end of the housing, a coupling and mounting plate defining means supported on said end of said housing and having a recess formed therein to receive either one of said coupling terminations and a bore to receive the other of said terminations, coupling means rotatably supported in said bore and engageable in coupling relation with the one of said coupling terminations located in said bore, and seal defining means interposed in sealing relation between said coupling means and said mounting plate bore for substantially preventing escape of fluid past said coupling means.

2. In a gear pump, a pump housing containing a pair of adjoining, substantially cylindrical chambers, said housing having a pair of ports formed therein on opposite sides thereof and communicating with said chambers, a pair of intermeshing pumping gears in said chambers, bearing bushing and end plate defining means associated with said pumping gears and supported in said housing, a shaft drivably associated with each of said pumping gears and rotatably supported in the associated bushings, a coupling termination formed on each of said shafts and extending beyond one end of said housing, said terminations being each located at the same end of the housing, a coupling and mounting plate defining means supported on said end of said housing and having a recess formed therein to receive either one of said coupling terminations and a bore to receive the other of said terminations, coupling means rotatably supported in said bore and engageable in coupling relation with the one of said coupling terminations located in said bore, seal defining means interposed in sealing relation between said coupling means and said mounting plate bore for substantially preventing escape of fluid past said

coupling means, a drain port in said pump, and means for venting fluid escaping past said seal defining means to said drain port.

3. In a gear pump, a pump housing containing a pair of adjoining chambers, said housing having a pair of ports formed therein on opposite sides thereof and communicating with said chambers, a pair of intermeshing pumping gears in said chambers, a shaft drivably associated with each of said pumping gears and rotatably supported in said housing, a coupling termination formed on each of said shafts and extending beyond one end of said housing, said terminations being each located at the same end of the housing, a coupling and mounting plate defining means supported on said end of said housing and having a recess formed therein to receive either one of said coupling terminations and a bore to receive the other of said terminations, coupling means in said bore engageable in coupling relation with the one of said coupling terminations located in said bore, and seal defining means interposed in sealing relation between said coupling means and said mounting plate bore for substantially preventing leakage of fluid past said coupling means.

4. In a gear pump, a pump housing having a pair of adjoining pumping chambers formed therein, said housing having a pair of ports formed therein on opposite sides thereof and communicating with said chamber, a pair of intermeshing pumping gears in said chambers for forcing fluid entering said chambers through one of said ports out of said chambers through the other of said ports, a shaft drivably associated with each of said pumping gears and rotatably supported in said housing, a coupling termination formed on each of said shafts and extending beyond one end of said housing, said terminations being each located at the same end of the housing, a coupling and mounting plate defining means mounted on said one end of said housing and having a recess formed therein to receive and enclose either one of said coupling terminations and a bore to receive the other of said terminations, and coupling means rotatably supported in said bore and engageable in coupling relation with the one of said coupling terminations located in said bore.

5. In a gear pump, a pump housing having a pair of adjoining pumping chambers formed therein, said housing having a pair of ports formed therein on opposite sides thereof and communicating with said chamber, a pair of intermeshing pumping gears in said chambers for forcing fluid entering said chambers through one of said ports out of said chambers through the other of said ports, a shaft drivably associated with each of said pumping gears and rotatably supported in said housing, a coupling termination formed on each of said shafts and extending beyond one end of said housing, said terminations being each located at the same end of the housing, a coupling and mounting plate defining means mounted on said one end of said housing and having a recess formed therein to receive and enclose either one of said coupling terminations and a bore to receive the other of said terminations, and seal defining means interposed in sealing relation between said coupling means and said mounting plate bore for substantially preventing leakage of fluid through said bore.

6. In a gear pump, a pump housing having a pair of adjoining pumping chambers formed therein, said housing having a pair of ports

formed therein on opposite sides thereof and communicating with said chamber, a pair of intermeshing pumping gears in said chambers for forcing fluid entering said chambers through one of said ports out of said chambers through the other of said ports, a shaft drivably associated with each of said pumping gears and rotatably supported in said housing, a coupling termination formed on each of said shafts and extending beyond one end of said housing, said terminations being each located at the same end of the housing, a coupling and mounting plate defining means mounted on said one end of said housing and having a recess formed therein to receive and enclose either one of said coupling terminations and a bore to receive the other of said terminations, seal defining means interposed in sealing relation between said coupling means and said mounting plate bore for substantially preventing leakage of fluid past said coupling means, a drain port formed in said pump, and passage defining means for venting fluid escaping past said seal defining means to said drain port.

7. In a gear pump, a pump housing having a pair of adjoining pumping chambers formed therein, said housing having a pair of ports formed therein on opposite sides thereof and communicating with said chamber, a pair of intermeshing pumping gears in said chambers for forcing fluid entering said chambers through one of said ports out of said chambers through the other of said ports, a shaft drivably associated with each of said pumping gears and rotatably supported in said housing, a coupling termination formed on each of said shafts and extending beyond one end of said housing, said

5 terminations being each located at the same end of the housing, a coupling and mounting plate defining means mounted on said one end of said housing and having a recess formed therein to receive and enclose either one of said coupling terminations and a bore to receive the other of said terminations, a drain port formed in said pump, a recessed drain area encircling said bore and spaced therefrom, and passage defining means communicating said drain area to said drain port.
